Primary Examiner — Rosemary K Tarcza(74) *Attorney, Agent, or Firm* — Greer, Burns & Crain, Ltd.;
Patty Chidiac; Mark W. Croll**(57) CLAIM**

The ornamental design for a battery pack for a combustion tool, as shown and described.

DESCRIPTION

FIG. 1 is a top perspective view of present battery pack;

FIG. 2 is a right side view of the battery pack of FIG. 1;

FIG. 3 is a left side view of same;

FIG. 4 is a front view of the battery pack of FIG. 1;

FIG. 5 is a rear view of same;

FIG. 6 is top view of the battery pack of FIG. 1; and,

FIG. 7 is a bottom view of same.

The broken lines shown in the drawings are included for the purpose of illustrating environmental structure and form no part of the claimed design.
